UNITED STATES PATENT OFFICE.

ADOLPH POTDEVIN, OF BROOKLYN, NEW YORK, ASSIGNOR TO POTDEVIN MACHINE COMPANY, OF BROOKLYN, NEW YORK, A CORPORATION OF NEW YORK.

MACHINE FOR APPLYING PASTE TO LABELS, &c.

1,040,009.

Specification of Letters Patent.

Patented Oct. 1, 1912.

Application filed August 12, 1910. Serial No. 576,893.

To all whom it may concern:

Be it known that I, ADOLPH POTDEVIN, a citizen of the United States, and resident of Brooklyn, in the county of Kings and State 5 of New York, have invented certain new and useful Improvements in Machines for Applying Paste to Labels, &c., of which the following is a specification.

This invention relates to a machine for 10 applying adhesive substance to labels or the like; my object herein being to provide an apparatus of simple and efficient construction and operation whereby the uniform application of the adhesive substance to the 15 lower surface of the labels shall be expeditiously effected, and the removal of the labels from the machine facilitated.

Accordingly my invention comprises various novel features of construction and 20 combinations of parts, which will be herein-after described and claimed.

In the drawings—Figure 1 is a front elevation of a machine embodying my invention. Fig. 2 is a plan thereof, with certain 25 parts broken away. Fig. 3 is an end view, with the driving gear partially broken away. Fig. 4 is a transverse vertical section, as on the line 4—4 of Fig. 1, showing a label as passing through and from the ma- 30 chine.

1 designates a suitable receptacle adapted to contain the adhesive substance in liquid state. This receptacle is provided with oppositely-inclined cover plates 2, 3, between 35 and above which extends a gum or paste applying roll 4 which is mounted to rotate within the tank and carry upward therefrom the liquid contents. The roll is herein shown as provided with trunnions which are 40 removably seated in slots in the ends of the receptacle, one of the trunnions being conveniently equipped with an ordinary crank handle 5 to facilitate the operation of rotating the roll.

45 6 is a scraper or doctor blade to regulate the thickness of gum or paste on the roller. This blade is adjustably mounted on posts 7 rising from the bottom of the receptacle, and is provided with depending lugs to 50 which are fitted adjusting screws 8 seated in the forward wall of the tank. Screw and slot connections 9 between the blade and the respective posts afford a means to secure the blade in its positions of adjustment with re- 55 spect to the surface of the roll.

10, 11 are two rollers which are rotatably mounted adjacent to and in parallelism with the periphery of the roll 4, and are respectively provided with pinions 12, 13 which mesh with a spur wheel 14 on a trunnion of 60 the roll, whereby when the latter is rotated the two rollers are concurrently actuated therewith. The forward roller 10, which has its bearings in the end walls of the tank, extends adjacent to the inner or rearward 65 edge of the forward cover plate 2 in a manner to engage the leading edge of the sheet or strip and feed it to and upon the periphery of the roll 4. The roller 11 is mounted above and in rear of the roller 10 and has its 70 bearings in vertically-adjustable slides 15 in the ends of the tank, whereby the roller 11 is adjustable toward and from the roll 4. These slides are fitted to vertical ways in the 75 end walls, and are vertically adjustable therein by means of set-screws 16 extending through suitably disposed brackets on the receptacle. The slides are secured in their positions of adjustment by means of screws 17 passing through slots 18 in the slides and 80 into the contiguous end walls.

As indicated in Fig. 4, a label (L) when introduced to the machine passes from the roller 10 to the roller 11, and in its passage contacts tangentially or substantially so 85 with the periphery of the roll, thereby insuring the uniform and efficient application of the adhesive substance to and throughout the under surface of the label. By adjusting the roller 11 toward or from the roll 4 90 I am enabled to compensate to a nicety for labels of varying thicknesses, to insure their efficient tangential contact with the roll and thus avoid undue pressure of the roller 11 upon the sheets. The roller 11, as will be 95 observed from the foregoing, acts as a holding roller for maintaining the labels in contact with the roll 4, while the roller 10 serves to feed the labels to said roll 4 and roller 11.

19 is a series of independently-movable spaced fingers which are adapted to bear with slight pressure upon the top of the roll 4 and immediately in rear of the roller 11 in a manner to present to the leading ends of the label a row of up-standing members 19^a 100 which deflect the label upwardly and forwardly from the roll as indicated in Fig. 4. These fingers are provided at their rearward ends with bosses which are loosely mounted 105 on a rod 20 supported in and between the 110

end walls of the receptacle, the other or forward portions of the fingers extending downward and resting by gravity on the roll. The lower ends and forward edges of 5 the members 19^a are beveled in a manner to present thin contact surfaces to the opposing label, and as the fingers are separated from each other and are independently movable, their action is not sufficient to impair the 10 uniformity of the gummed surface of the label. The fingers may be adjusted along the shaft to accommodate labels of different widths, and moreover if one or more of the fingers should become bent or broken, it or 15 they may be readily removed and another or others substituted therefor.

The action of the up-standing members 19^a is to deflect, as stated, the gummed labels upwardly and forwardly from the adhesive- 20 applying roll after application of the adhesive substance to the labels, whereby the labels are delivered toward the front of the apparatus with the gummed face up. By reason of this one attendant is enabled to 25 feed the labels, take them off, and inspect the gummed surface.

I do not limit myself to the specific details of construction herein shown and described, but

30 What I claim is:—

1. In an apparatus for applying adhesive substance to labels, &c., the combination with a receptacle, and a rotatable roll therein, of a pair of rollers mounted adjacent said 35 roll in advance of the axis thereof and in different horizontal planes, the lower of said rollers serving to feed the labels to said roll and the upper roller serving to hold the labels in contact with 40 the periphery of the roll, and means arranged in rear of said rollers and over the top of said roll for deflecting the labels upwardly and forwardly from the roll after application of the adhesive substance to the 45 labels.

2. In an apparatus for applying adhesive substance to labels, &c., the combination with a receptacle, and a rotatable roll therein, of a pair of rollers mounted adjacent said roll 50 in advance of the axis thereof and in different horizontal planes, the lower of said rollers serving to feed the labels to said roll and the upper roller serving to hold the labels in contact with the periphery of the

roll, said lower roller being adjustable relatively to said roll for compensating for varying thicknesses of labels, and means arranged in rear of said rollers and over the top of said roll for deflecting the labels upwardly and forwardly from the roll after 60 application of the adhesive substance to the labels.

3. In an apparatus for applying adhesive substance to labels, &c., the combination with a receptacle, and a rotatable roll therein, of 65 a pair of rollers mounted adjacent said roll in advance of the axis thereof and in different horizontal planes, the lower of said rollers serving to feed the labels to said roll and the upper roller serving to hold the 70 labels in contact with the periphery of the roll, and a series of independently-movable fingers mounted over the top of said roll and adjacent the periphery thereof and provided with up-standing forward portions adapted 75 to bear yieldingly upon the top of said roll.

4. In an apparatus for applying adhesive substance to labels, &c., the combination with a receptacle, and an adhesive-applying roll associated therewith, of means for feeding 80 the labels to said roll, and a member supported adjacent the roll and provided with means for deflecting the labels upwardly and forwardly from the roll after application of the adhesive substance to the labels, 85 whereby the labels are delivered toward the front of the apparatus with the gummed face up.

5. In an apparatus for applying adhesive substance to labels, &c., the combination with 90 a receptacle, and an adhesive-applying roll associated therewith, of means for feeding the labels to said roll, and a finger mounted adjacent the periphery of the roll and having a label contact portion extending upwardly from the roll and adapted to deflect the labels upwardly and forwardly after application of the adhesive substance to the labels, whereby the labels are delivered toward the front of the apparatus with the 95 gummed face up.

Signed at Brooklyn, N. Y., in the county of Kings and State of New York this 3d day of August A. D., 1910.

ADOLPH POTDEVIN.
